INVENTOR
George E. Nerney
BY Janney, Blair + Curtis
ATTORNEY

UNITED STATES PATENT OFFICE

GEORGE E. NERNEY, OF ATTLEBORO, MASSACHUSETTS, ASSIGNOR TO BAY STATE
OPTICAL COMPANY, A CORPORATION OF MAINE

DEVICE FOR MANICURING

Application filed April 14, 1930. Serial No. 444,083.

This invention relates to implements for manicuring.

Among the objects thereof are to provide a simple and practical device of the above nature, a device of such nature convenient to use and efficient in action, and such a device of compact construction and which can readily be carried in the pocket. Other objects will be in part obvious and in part pointed out hereinafter.

The invention accordingly consists in the features of construction, combinations of elements, and arrangements of parts, as will be illustratively described herein, and the scope of the application of which will be indicated in the following claims.

In the accompanying drawing, in which is shown one of various possible embodiments of this invention,

Figure 1 is a perspective view thereof;

Fig. 2 is a sectional view taken along the line 2—2 of Fig. 1; and

Fig. 3 is a detail perspective on an enlarged scale of a portion of the device shown in Fig. 1.

Similar reference characters refer to similar parts throughout the several views of the drawing.

Referring now to the drawing in detail, the part 10 is formed of a sheet of metal, preferably steel or an alloy thereof, and is substantially flat and preferably of substantially elliptical outline. It may here be noted that the term "elliptical" is used in a broad sense to cover any shape approximating an ellipse, including a circle, which may be considered an ellipse of equal axes.

The part 10 is provided about its edge, which is concave as indicated at 11, with serrations 12 to form a nail file. It is also preferably provided adjacent its edge portions on its flat surface with a bordering file surface 13, although this is not essential in the broader aspects of the invention.

At one point along the edge of the disk 10 there are provided a pair of recesses 15 within which are seated the flanges 16 of a nail cleaning device 17 having a prong 18. The device 17 is pivoted as at 19 to the part 10 and is adapted to fold down-

wardly upon the edge, as indicated in the dotted lines, so as to have its flanges fit within the respective recesses and have its prong portion substantially embraced by the concave edge.

In this manner the entire nail cleaning device is in its closed position substantially embraced within the outline of the disk 10, and it may be releasably held in such closed position by means of projections 20 formed in the inner walls of the flanges adapted to snap into suitable notches 21 formed in the disk. It may here be noted that the term "disk" is used in a broad sense to cover any substantially flat member having a substantial degree of width as compared with its length, and it may also be noted that the term "rounded" is broadly used.

In the use of the device as a file, the edge portion may be employed effectively and is adapted to gain easy access to parts of the finger-nail which are difficult or uncomfortable to attack with a manicure file of the ordinary form. Furthermore, the shape of the disk readily affords a firm grasp during the use of the device, whether it be for filing or cleaning the nails. It may also be noted that the edge of the disk affords a convenient means for pushing back the cuticle from the nail. If it be desired to clean the nails, the resilient member 17 is snapped out of its closed position into the raised position shown in Fig. 3, whereupon it may conveniently be handled and thereafter be snapped into closed position.

The compact conformation of the entire device will be clear, and it will also be seen that it is readily carried in the pocket without the chance of perforation of the pocket lining.

It will thus be seen that there is provided a device in which the several objects of this invention are gained and that the same is well suited to meet the conditions of practical use.

As many possible embodiments may be made of the above invention, and as many changes might be made in the embodiment above set forth, it is to be understood that all matter hereinbefore set forth or shown

in the accompanying drawing is to be interpreted as illustrative and not in a limiting sense.

I claim:

- 5 1. In a manicuring implement, in combination, a rounded disk, the edge portion of which is formed as a file and having mounted thereon a nail cleaning device adapted to swing toward and away from
10 the periphery of said disk.
2. In a manicuring implement, in combination, a file member, and a nail cleaning member pivotally mounted on the periphery thereof to swing toward and away
15 from the periphery and shaped to substantially embrace the periphery when it is swung inwardly.
3. In a manicuring implement, in combination, a substantially flat member having
20 a file portion formed along its edge, and a nail cleaner positioned substantially within the outline of said first member and mounted thereon to move outwardly and project beyond the periphery thereof.
- 25 4. In a manicuring implement, in combination, a substantially elliptical disk having a concave file surface at its edge and extending substantially about the same, and a nail cleaning member movably mounted
30 thereon and adapted to be moved outwardly from the periphery of said disk to project into position for use.
- 35 5. In a manicuring implement, in combination, a substantially elliptical disk having a concave file surface at its edge and extending substantially about the same, and a nail cleaning member movably mounted thereon and adapted to be moved outwardly from the periphery of said disk to project
40 into position for use, said nail cleaning member being pivoted adjacent the edge of said first member to swing toward and away from the same.
- 45 6. In a manicuring implement, in combination, a substantially elliptical disk having a concave file surface at its edge and extending substantially about the same, a nail cleaning member movably mounted thereon and adapted to be moved outwardly from
50 the periphery of said disk to project into position for use, said nail cleaning member being pivoted adjacent the edge of said first member to swing toward and away from the same, and means adapted releasably to hold
55 said last member in its innermost position.

In testimony whereof, I have signed my name to this specification this 18th day of March, 1930.

GEORGE E. NERNEY.
